UNITED STATES PATENT OFFICE.

JOHN STUBBLEFIELD, OF COLUMBUS, NEBRASKA, ASSIGNOR OF ONE-FOURTH TO WILLIAM H. STUBBLEFIELD AND ONE-FOURTH TO HENRY R. SEIDEL, BOTH OF COLUMBUS, NEBRASKA.

DRAFT DEVICE FOR FURNACES.

Application filed April 30, 1925. Serial No. 26,979.

To all whom it may concern:

Be it known that I, JOHN STUBBLEFIELD, a citizen of the United States, residing at Columbus, in the county of Platte and State 5 of Nebraska, have invented certain new and useful Improvements in Draft Devices for Furnaces, of which the following is a specification, reference being had to the accompanying drawings.

10 This invention relates to furnaces, and particularly to the draft devices thereof.

It is usual in installing heating furnaces in houses to place them in the cellar or furnace room, these heating furnaces having 15 draft openings provided with dampers or doors, which draft openings open directly into the cellar or furnace room. As a consequence, the air which is delivered to the fire is usually contaminated and lacks oxy-

20 gen, the oxygen having been used up by the fire itself, and thus the best results are not secured from the furnace under these circumstances but the fire is liable to be dull and the combustion imperfect and much less

25 heat is secured than should be secured and much more labor entailed. In order to avoid this it is more or less common to open a door or window from the outside to admit outside air into the cellar or furnace room 30 but this acts to chill the furnace and to chill those pipes which pass through the furnace room, thus wasting heat and necessitating a greater amount of coal being burned.

The object of my invention is to provide 35 a furnace and particularly furnaces such as are used in large houses and apartments or plants of like character with a pipe which extends from a draft door to the outside air, this pipe being provided with a damper 40 whereby a sufficient supply of fresh air with its full quota of oxygen is provided for the furnace.

A further object in this connection is to provide an attachment of this nature which 45 may be applied to any furnace for this purpose.

My invention is illustrated in the accompanying drawing, wherein:—

Figure 1 is a front elevation of a furnace 50 of common construction showing my cold air draft appliance thereon in section;

Figure 2 is a vertical sectional view through the cold air draft appliance, the furnace being partly broken away.

Referring to this drawing, it will be seen 55 that I have illustrated a common form of furnace, this furnace not constituting any part of my invention and merely being to illustrate an application of my invention. This furnace A is of the over draft type, 60 that is, it has a draft opening B which is disposed below the level of the fire but above the grate C. Below the grate there are disposed the ash doors D and above the grate the clinker doors E in this form of furnace. 65 Disposed in the upper portion of the furnace are the feed doors F. The stack is designated G and the draft up the stack is regulated by means of a check draft damper of the usual character. It will be understood 70 that I do not wish to limit myself to this particular form of furnace but I have merely illustrated a common type.

75 My invention consists in applying at the draft opening B the casing or head 10 having therein a controlling damper 11, and from this casing or head extends a pipe 12 which extends vertically for a distance and then is angularly bent at 13 and extends out through the adjacent wall of the basement and opens to the fresh air so that the fresh air can pass through this pipe and down to the head 10 and thus be discharged into the interior of the furnace preferably, in the 80 form of furnace illustrated, at a point just 85 above the fire.

This head 10, as illustrated, is designed to fit over the rectangular box-like frame which defines the inlet opening B, and inwardly of this opening there is a downwardly extending baffle wall b which may extend the entire length of the furnace and which acts to deflect the air longitudinally through the length of the furnace and downwardly to a position beneath the fire 90 but above the grate.

95 While I have illustrated this fresh air draft pipe and head as being applied to one type of furnace, it is intended that the head shall be so formed as to fit the draft door frames of different furnaces and heads may be made and kept in stock for the standard forms of furnaces. Thus, for instance, in a furnace where the fresh air is admitted to the fire through the lower draft door or through a draft damper in the furnace base, the fresh air head 10 will be designed to fit the opening or the projecting 100 105

flange defining said opening. By controlling the damper 11, the amount of fresh air entering the fire will be controlled in the usual manner.

- 5 By means of my appliance pure, fresh air is piped directly from the outside of the building into the combustion chamber of the furnace and by drawing this pure, fresh air through the fire causes it to warm
10 up by the time it comes in and by mixing plenty of this pure, fresh air with the gases they are burned up and the fuel waste practically eliminated and fuel smoke also disappears. Atmospheric air includes approx-
15 imately 20% of oxygen, while the air in the average furnace room is probably as low in oxygen content as 12% or 15%, and it has been found by actual experiments and tests that a difference of 2% of oxygen
20 in the air passing into a fire will make a very great difference in the completeness of its combustion. I have found in actual practice that this is the case. For instance, in the particular building in which the fur-
25 nace I have experimented on is located, there are two boilers, the furnace being of the magazine feed down-draft type. The fuel recommended for this furnace is #3 free burning soft coal. During the past
30 winter in testing this device I used in this furnace a rather poor quality of slack lig-

nite coal. It has been heretofore very difficult with both furnaces going to heat the building, but this past winter with my appliance attached to one of the furnaces and 35 the other furnace completely idle with no fire in it at all, and burning the poorest slack lignite coal, the building has been kept very warm even in the coldest weather and at least thirty tons of coal have been saved. 40 It will, therefore, be seen that my invention is of practical value and greatly reduces the consumption of coal as well as adding to the heat generated by the coal. Obviously, 45 the installation will be modified to suit circumstances of operation.

I claim:—

The combination with a furnace having a draft opening disposed above the grate and below the normal level of the fuel bed, 50 the draft opening being defined by outwardly extending walls and the walls carrying a damper, of a pipe having a head at one end fitting over the outwardly extending walls of the draft opening, the other end of the pipe extending to the exterior of the building and opening into a source of pure, fresh air.

In testimony whereof I hereunto affix my signature.

JOHN STUBBLEFIELD.
